UNITED STATES PATENT OFFICE.

JOHN C. MACKEY, OF SYRACUSE, NEW YORK.

AUTOMATIC FIRE-EXTINGUISHER.

SPECIFICATION forming part of Letters Patent No. 366,177, dated July 5, 1887.

Application filed December 4, 1886. Serial No. 220,739. (No model.)

To all whom it may concern:

Be it known that I, JOHN C. MACKEY, a citizen of the United States, residing at the city of Syracuse, in the county of Onondaga, State of New York, have invented certain new and useful Improvements in Automatic Fire-Extinguishers, of which the following is a full, clear, and exact description, reference being had to the accompanying drawings, in which—

10 Figure 1 represents a vertical sectional view of my improved fire-extinguisher with the valve closed. Fig. 2 represents a similar view showing the valve released. Fig. 3 represents a bottom plan view of the deflector with the locking-plate in position. Fig. 4 represents a 15 top plan view of the same, showing the details of its construction. Fig. 5 is a side elevation of the deflector, showing the supporting studs. Fig. 6 is an isometric view of the valve disk. 20 Fig. 7 is a similar view of the valve-stem.

My invention relates to automatic sprinklers or fire-extinguishers; and it consists in the construction and combination of devices hereinafter described and claimed.

25 To enable others to become skilled in the art to which my invention appertains, I will now describe the manner in which I have carried it out.

The device herein described and illustrated 30 is for use in extinguishing a fire that may occur within a structure or room of a building, and is designed to be placed in the upper part of a room or structure, and adapted to a pipe or conduit for carrying water or chemicals under pressure into the chamber of said device.

35 In the said drawings, A A' represent the body of the sprinkler, which is divided horizontally at or near the center, the upper portion, A, being threaded and capable of attachment to a pipe or conduit containing water or chemicals under pressure, a flange, 1, serving as a nut, whereby the body A is screwed to the pipe or conduit. The upper portion of the body is provided with a seat, 2, against which 40 is securely held a suitable valve, the construction and operation of which will be hereinafter described. The lower portion, A', of the body is provided with a discharge-aperture, C, and is perforated to receive the upper ends 45 of screws or bolts D, which connect said body with a deflector, E. This deflector E has a

central perforation, 3, which guides the movements of a suitable valve-stem, and also has a series of double inner projections, F F', the inner series, F, being arranged around the central perforation, 3, and directly beneath the discharge-aperture C in the body A, while the projections of the second series, F', are formed around the deflector near its outer circumference.

55 From this description it is manifest when the valve is released from its seat the volume of water or chemical in its descent comes in contact with the inner series of projections, F, and thereby divides the liquid, which is forced outward by the pressure in the pipe or conduit until these divided streams come in contact with the outer series of projections, F', when the water is again divided, this time in finer streams, which are forced upward by the deflector against the ceiling of the structure and descend upon the fire in fine sprays. The arrangement of the double series of deflectors 60 enables the water to be discharged not only in finer streams, but also to cover an area much 65 larger than if a single row of projections or a flat disk were employed to deflect the water or chemical.

70 The valve G in the present case consists, essentially, of a disk mounted upon the upper 75 end of a valve-stem, H, and provided with a soft-metal face, K, adapted to come into contact with the rounded edges of the valve-seat, and thereby form an absolutely tight joint between the two. It will be observed the 80 valve is located at the extreme upper end of the body A, and is designed to prevent the water or chemical from entering the body of the 85 sprinkler until the temperature of the room or structure fuses the solder which retains the valve in position, and also prevents all liability of the liquid freezing and thereby arresting the 90 successful movements of the device.

95 As before stated, the valve is attached to the upper end of the valve-stem H, and has a shoulder, 4, upon its lower face, which is designed to come into contact with and find a seat upon suitable pins, 5, projecting upwardly from the inner face of the lower portion of the body, as shown in Fig. 2. The valve-stem projects downward into the aperture 3, and when the valve is closed the lower end of the stem 100

is nearly flush with the lower face of the deflector. Upon the bottom of the deflector I place two studs, M O, each of which is notched, as is shown in the drawings.

5 Upon or astride of the stud M, I place the spring R, one end of which is slotted to fit over the stud, and by catching under the notch 6 it has a spring-bearing upon the stud.

N is a plate of metal provided with slots 7 10 8, of proper size to fit loosely over the studs, and when placed in position oneslot, 7, catches under the notch 9 of stud M and the central portion bears against the spring R, compressing it against the bottom of the valve-stem, holding the valve closed, and the other end of this plate is passed over and partly 15 upon the stud O, where it is soldered fast by a drop of solder, which is fusible.

It will be thus observed that in the event of 20 fire breaking out in a room or structure in which the device is located the solder uniting the plate N with the deflector-stud O melts and permits said plate to be thrown off by the 25 spring R, it and the spring falling, and said stem dropping to its seat upon the pins 5. The water or chemical being thereby released is discharged upon the fire and extinguishes it.

Having described my invention, what I 30 claim, and desire to secure by Letters Patent, 3c is—

1. The combination, with a body having an annular valve-seat at its extreme upper end, of a valve-stem, a valve secured to said stem and provided with a soft-metal face which engages the seat, a deflector having flanges, bottom studs, M O, a spring, R, and a plate fitting over one stud and adapted to be soldered to the other stud, substantially as shown and described. 35

2. In an automatic fire-extinguisher, a valve 40 support consisting of a spring connected to a stud projecting from the deflector and bearing against the bottom of the valve-stem and a cross-bar compressing said spring and fusibly connected to studs projecting from the deflector, substantially as described. 45

3. In an automatic fire-extinguisher, a deflector suspended from the body and provided with bottom studs, in combination with a valve-stem, a spring connected to one stud, 50 and a cross-bar bearing against the free end of the spring and fusibly connected to the studs, substantially as shown and described.

In witness whereof I have hereunto set my hand this 16th day of November, 1886.

JOHN C. MACKEY.
